UNITED STATES PATENT OFFICE.

ALFRED LOTZ, OF CHICAGO, ILLINOIS, CHARLES J. DAVIDSON, OF MILWAUKEE, WISCONSIN, AND WILLIAM J. KENNEY, OF CHICAGO, ILLINOIS, ASSIGNORS, BY MESNE ASSIGNMENTS, TO MOLOCH COMPANY, OF KAUKAUNA, WISCONSIN, A CORPORATION OF WISCONSIN.

GRINDER MECHANISM FOR BOILER FURNACES AND THE LIKE.

Application filed August 12, 1920. Serial No. 402,991.

To all whom it may concern:

Be it known that we, ALFRED LOTZ, CHARLES J. DAVIDSON, and WILLIAM J. KENNEY, citizens of the United States, residing at Chicago, in the county of Cook and State of Illinois, Milwaukee, in the county of Milwaukee and State of Wisconsin, and at Chicago, in the county of Cook and State of Illinois, respectively, have invented a certain new and useful Improvement in Grinder Mechanism for Boiler Furnaces and the like, of which the following is a full, clear, concise, and exact description, reference being had to the accompanying drawings, forming a part of this specification.

Our invention relates to grinder mechanism for furnaces and the like and is an improvement over the Patent Number 1,372,652, granted to C. J. Davidson and William J. Kenney on March 22, 1922.

Grinders of the general class described, are employed for removing the refuse or non-combustible product from boiler furnaces, drying furnaces, or furnaces of any description and purpose. These grinders are frequently used in conjunction with automatic stokers, the arrangement being such that the grinders and the stokers are automatically actuated, the furnace being automatically fired by the stoker and automatically cleaned of refuse by the grinders.

In the mounting of grinders of this general class, it is necessary, in order that efficient and proper operation may be obtained to the end of acquiring maximum performance of the furnace, to mount the grinder adjacent the furnace retort, so that, as the volatile gases are burned, the coke is permitted, due to expansion, to spread over the tuyère plate and reduce to non-combustible refuse or slag. This, therefore, exposes the surface of the grinder adjacent the retort bed to intense heat. We have found that the main obstacle to the successful use of these grinders has been that of maintaining them due to this high temperature of combustion. Depreciation occurs due to burning, cracking and mechanical difficulties incident to the large expansion and contraction caused by the intense heating. Although various and numerous methods of cooling the grinder have been proposed, the

inadequacy of them has failed to overcome the difficulties.

In various experiments, it has been found by the use of various testing apparatus that, regardless of the methods of cooling employed, the formation of air or steam pockets adjacent the fire zone area of the grinder is unavoidable so long as the grinder lies in a horizontal plane. The rate of flow of the cooling medium becomes an insignificant factor as soon as the temperature rises, as the creation of steam constantly increases the size of the pocket which results in forcing the discharge level below the mouth of the outlet, permitting the upper portion of the grinder to be exposed.

It is the primary object of the present invention to so arrange the grinder within the furnace, that the hottest portion of the grinder, lying adjacent the fire zone, is in continuous and constant contact with the cooling medium. This is accomplished by mounting the rotatable grinder in a plane inclined to the horizontal plane. The air or steam pocket then formed is trapped at the upward forward end of the inclined grinder, at which point the outlet is provided. The circulation of the cooling medium is such that a constant upward flow is maintained, which tends to trap all air or steam in a part which is remote from the fire zone. We believe that we are the first to discover that by inclining the grinder, a constant contact of the cooling medium with the surface adjacent the fire zone is obtained, and consequently claim the same broadly.

In the grinder embodying our invention, the ends are supported upon opposite walls of the furnace for permitting the grinder to rotate. While it is not essential that the grinder rotates in order to embody the important feature of the invention, however, many advantages are gained in the operation of the grinder in having the entire periphery made subject to the heat of the fire bed. One of the most important advantages is the extended life and the distribution of the wear over the entire outer surface. By having the entire body of the cylinder subject substantially to the same temperature, local overheating is overcome and the mechanical difficulties incident to

concentrating the heat over a certain area only is eliminated. Even radial expansion and contraction will be had as well as a resulting similar action in a longitudinal direction. Even expansion and contraction in one direction is dependent upon an even expansion and contraction in the other. Holding the water in close contact with the upper surface of the interior will also prevent local overheating of the grinder walls.

A further object is in the method of circulating the cooling fluid for effectively cooling the grinder and preventing steam or air pockets from forming. Water is introduced into the grinder so that, with the inclined position thereof, a distinct circulation is created due to two separate tendencies, first the tendency for the cold water to sink due to its greater weight and second the tendency for the hot water to rise due to expansion.

This circulation includes a downward flow of the relatively cold water along the lower surface of the grinder drum and an upward flow of the heated water along the upper wall of the drum. As the drum revolves each element of the surface comes into contact with both these streams.

In the accompanying drawings, we have illustrated our invention as embodied in several forms of boiler furnaces, which are equipped with both the underfeed and overfeed stokers, and lying in an axis parallel to the retort as well as transverse. However, it is apparent that this showing is illustrative merely, and many forms and arrangements may be had.

In the drawings:

Figure 1 is a longitudinal vertical section of the inclined grinder with a portion of the driving mechanism removed;

Figure 2 is a side elevation of the same;

Figure 3 is a side end view of the same, illustrating the inlet and discharge pipe;

Figure 4 is a detailed view taken on line 4-4 of Figure 1, illustrating the arrangement of the intake and exhaust passages;

Figure 5 is a view of the driving of the grinder, illustrating the regulating mechanism employed to intermittently rotate the grinder;

Figure 6 is an end view of the same, illustrating the regulating disc employed for varying the degree of rotation;

Figure 7 is a detail view of the cover plate employed;

Figure 8 is a longitudinal vertical section of a furnace wherein is embodied the inclined grinder, illustrating the manner of supporting same;

Figure 9 is a transverse sectional view of another type of furnace, illustrating the embodiment of the grinder at each side of the retort and the manner of distributing the fuel over the tuyère plate upon the grinder;

Figure 10 is a longitudinal section of a typical underfeed stoker furnace equipped with our improved grinder mechanism; and

Figure 11 is a transverse view of a side overfeed center cleaned stoker furnace equipped with our improved grinder mechanism.

The grinder illustrated in Figures 1 and 2 is particularly adapted to be disposed adjacent the retort of the furnace in a plane inclined to the horizontal, the degree of which depending on the particular adaptation or needs. In this position the grinder is capable of performing efficiently, and the novelty resides in the fact that the cooling water is constantly in contact with the entire upper surface of the shell, except that portion immediately adjacent the outlet passage. The level is such at this portion, that regardless of the steam, which might tend to form, it is impossible to force the water away from the surface of the grinder immediate the fire zone.

In this form the grinder comprises a shell 70, the rear end of which is closed off by a trunnion cap 71, the shell being provided with a plurality of studs 72 arranged about its surface. As shown in Figure 1, the trunnion cap 71 is threaded on the cylindrical shell 70, displacement of the trunnion cap upon rotation of the cylinder being effectively prevented by means of the stud bolt 73, which is threaded through the cap 71 and into the shell 70. A gear collar or ferrule is threaded on the opposite end of the cylindrical shell 70, displacement of this collar or ferrule upon rotation of the grinder being prevented by means of a head stud 75 which extends through the collar 74 and shell 70. The gear collar 74 is provided about its periphery with a pair of operating arms 76 and 77, these operating arms being provided with a ring portion at the upper end which loosely engages the collar 74, having a free connection therewith, and at the lower end provided with a depending arm portion which will be described later. These operating arms 76 and 77 are suitably spaced for the reception of the driving gear 78 therebetween. A key 80 co-operating with suitable keyways in the collar 74 and the advancing or driving gear 78, serves to rigidly secure the gear 78 upon the gear collar 74. The last mentioned members in reality form part of the automatic advancing mechanism which is to be described hereinafter, but have been here mentioned as they in part form a portion of the head at this end of the grinder.

As shown in Figure 2, the studs 72 are of stock material, if desired, taper threaded into the grinder shell and may be easily and cheaply renewed. The studs are mounted about the shell 70 to crush the clinkers at different points successively along the

length of the grinder surface, and thus to minimize and distribute the effect of this crushing action to a complete revolution of the grinder cylinder.

5 The front end of the cylindrical shell 70 is closed off by means of an annular disc or plate 81, which is adapted to be clamped to the collar or ferrule 74 by means of the bolts 82, an annular flange projecting inwardly from the disc 81 cooperating with the interior of the shell 70. The disc 81 is provided with a suitable bore substantially in the center thereof for the reception of the end pipe head 83. The inner end of the pipe 83 is enlarged thereby providing a suitable shoulder which serves as an annular recess to form a stuffing box in which is lodged the packing 84. The disc 81 is provided with an annular flange 85 projecting inwardly therefrom about the bore provided therein, this flange serving as a gland for cooperating with the packing 84 to form a tight joint about the pipe head 83. The pipe head 83 is threaded adjacent the annular disc 81 for the reception of a tension ring 86 thereon, which is adapted to be threaded up into engagement with an annular bore surrounding the bore provided in the disc 81. Upon threading the tension ring 86, either inwardly or outwardly upon the pipe head 83, the compression on the packing 84 may be adjusted to prevent leakage of water without causing undue friction between the rotating disc 81 and the stationary pipe head 83. A set screw 87 is provided for securely locking the tension ring 86 against incidental displacement.

The pipe head 83 is cored out to provide a water inlet passage 88 therein, the inner end of this passage being threaded to receive a water inlet pipe 89, the axis of which is substantially parallel with the axis of the cylindrical shell 70. The inner free end of the pipe 89 is provided with an elbow 90 whereby the cold inlet water is fed into the bottom of the cylindrical shell 70. It is to be here noted that the provision made causes the flow of the inlet water to travel a downward path, first distributing itself throughout the lower portion of the cylindrical shell 70 and contacting with the lower walls before rising to the upper portion. This insures efficient cooling throughout the grinder. The water upon heating immediately rises, coming into contact with the hottest portion of the shell 70, which not being the highest point within the shell permits the water, by thermo-action to continue circulating. Thus a constant and positive circulation over the hottest surface of the shell 70 is assured.

The cooling water is fed into the inlet passage 88 by way of an inlet pipe 91 which is threaded into the pipe head 83 as shown in Figure 4.

A discharge pipe 92 is threaded into the pipe head 83 and communicates with the discharge passage 93, as shown in Figures 1 and 4. The heated water is discharged into the discharge passage 93 by way of the upwardly extending passage 94, the heated water being withdrawn from the discharge passage 93 by way of the discharge pipe 92.

It will now be apparent that upon feeding the cold water into the pipe head and inlet pipe, the shell 70 will be effectively cooled, the water level in the shell 70 being maintained at substantially the level of the outlet passage 94, as shown in Figure 1. Thus any steam generated in the shell 70 and any air fed in with the inlet water will immediately rise to the top of the shell, which in this case, is that particular portion immediately adjacent the outlet passage 94, from where it is instantly vented through the outlet passage. By discharging the water adjacent the top of the shell 70, the outlet passage 94 exhausts the water as soon as it becomes heated and rises to the top of the shell 70.

The particular arrangement and relation of the inlet pipe 89 and discharge outlet to the inclined grinder, creates a method of cooling the grinder that insures positive action of the cooling fluid. The downward turned elbow 90, from which the cold water is discharged into the interior of the grinder, and the downwardly sloping lower surface of the interior of the grinder cause a circulation from the entire lower portion to the upper portion. At the rear end, where the upper surface is lowered, with respect to the horizontal, due to inclining the grinder, the cooling water has two forces positively moving it in contact along the grinders upper surface until it reaches the outlet 94. The first force is that of the circulation due to the cold water emitting from the inlet 89 and spreading throughout the lower area. The second force is that of thermo-action, being established by the hottest portion of the grinders upper surface not being the highest point, and hence, as the water heats up, it tends to rise to the top. The top, in the present grinder, is that area adjacent the outlet 94, and is without the furnace to avoid the inevitable result which happens when the fire bed works forward to the front wall of the furnace. The circulation being positive, there is no possibility of the flow jumping from inlet to outlet without first passing around the entire interior.

This form of grinder may be advanced through the gear 78 in substantially the manner as shown in Figures 5, 6 and 7, or in any preferred manner.

By referring to Figures 5 to 7, the advancing or driving gear 78, as before mentioned, is keyed to the collar 74, which is

fixed upon the cylindrical shell 70, so that, as the gear 78 is driven, the shell 70 will in turn rotate. The operating arms 76 and 77 lying oppositely adjacent the gear 78 are free to revolve upon the collar 74, these being retained from displacement upon the collar 74 by the integral circumferential flange 74' and the projecting edge of the disc 81. A projection is provided at the outer end of the pipe head 83 into which is drilled threaded screw holes 83'. This end of the cylindrical grinder is provided with a housing or cover member 121 which is adapted to be disposed over the advancing gear 78 and the upper portion of the operating arms 76 and 77. The housing or cover member 121 is semicircular in formation, having the lower part open. The reduced portion 123 formed on the outer end of the cover 121 is provided with a plate 124, the plate serving as a cover for the front end of the grinder. The hollow bearing boss 125 is centrally formed upon the plate 124 to receive the projecting end of the pipe 83 which forms a loose bearing for the same, thereby permitting the cover to revolve if desired. To the face of the projecting end of the pipe head 83 there is rigidly secured by means of bolts 126 a regulating disc 127 with a notch arm 128 extending upwardly. This arm 128, as shown in Figure 6, is notched so that the movement of the cylindrical shell may be regulated if desired. To this end, a regulating finger 129 is pivotally carried by integral lugs 130 of the cover 121, the finger 129 having a locking detent 131 adapted to engage with the notches. The diametrical ends of the cover 121 are formed with apertured ears or lugs 132, preferably a pair at each end, so that a regulating or guiding plate 133, arcuated in formation, may be alternately carried at either end. The regulating plate 133 is pivotally carried by means of the pintle member 134 secured in the ears 132 by a cotter pin, regulating plate 133 being rigidly held in position by the locking bolt 135 threading in the plate 133 and against the cover 131. This provides a ready means of disassembly of the plate 133. The operating arms 76 and 77 are pivotally provided with a gravity pawl 136 which lies adjacent the regulating plate 133 with the hook 137 engaging the under side thereof. A bolt 138 passes through the operating arms 76 and 77 and through a sleeve 139 disposed within the gravity pawl 136. The operating arms 76 and 77 are reciprocally actuated by the usual driving mechanism, a pin riding in the slot 140 at the lower end of the arms, so as to swing the arms in a path of a limited arc. As shown in the drawings, the arms 76 and 77 swing in the direction of the arrow, the pawl rides past the regulating plate until the arms reach the limit

of their movement in that direction, whereupon the hook 137 drops into engagement with the advancing gear 78. Upon return travel of the arms 76 and 77 the pawl 136 advances the gear 78, the regulating plate 133 serving to control the degree of advancement of the gear 78 by limiting the engagement of the pawl 136 with the gear. This operation is repeated and thus it is to be seen that the grinder is periodically rotated. The degree of advancement of the gear 78 is dependent upon the position of the regulating finger 129. As shown in Figure 6, the finger 129 is set at 0, which indicates that the grinder is not being rotated. This is sometimes desirable, as would be the case where a series of grinders is being driven by a common driving mechanism and it should be necessary to shut down on the running of one unit or so.

It is to be noticed that we have provided means whereby a reversal of the direction of rotation may be had when necessary. In furnaces of the multi-retort type where it is necessary to employ a grinder between each retort, the method of burning the fuel requires that the adjacent grinders rotate in opposite direction. In order to allow for this without causing necessary changes in the construction of the automatic advancing mechanism, the regulating plate 133 is transposed to the opposite diametrical ears 132 and the pawl 136 reversed in position. The pawl 136 will then advance the gear 78 when the operating arms 76 and 77 travel in direction opposite to that shown by the upper arrow in Figure 6.

In Figure 8 we have shown embodied in an under feed type of furnace with an inclined grinder and the manner of supporting the same in the furnace. The arrangement of the furnace comprises the rear wall 145, the front wall 146 and the side wall 147 with the tuyère block 148 extending parallel thereto. The upper tuyère blocks are disposed in stepped relation to each other in order to provide draft openings which open into the retort. The lower tuyère blocks are in forms of aprons which lie adjacent to and form longitudinal pockets between the grinder, so that the refuse may be discharged therethrough on to the dumping doors 149. The rear end of the grinder is rotatably supported in the bearing pedestal 150, suitable carried by the concrete foundation. The front end of the grinder is similarly supported by the bearing pedestal 151, also carried by the concrete foundation at this end. It will be apparent, though, that any form of support may be provided for the ends of the grinder.

The front end of the grinder is projected through the opening in the front end of the furnace with the automatic advancing mech-

anism on the outside, as is preferred. This end of the furnace is closed off by a suitable casing 152 having an opening therein to permit the grinder to pass through, and an 5 upper member 153 which slopes slightly to the coal bed, ending in a downwardly extending flange 154 to prevent the bed from working back upon the grinder. It is to be noted that the upper portion of the 10 grinder, free from contact with the fire bed, is that portion adjacent the outlet 94 in which the air or steam is allowed to accumulate before being exhausted. This portion will be known as the "upper portion of the 15 grinder remote from the fire zone".

In Figure 9 we have shown our improved grinder mechanism in connection with a typical side underfeed furnace. In this case the furnace comprises side walls 96 and 20 97 and a rear wall 98. The coal is carried into the furnace by suitable feeder mechanism, (not shown), the coal being forced to rise the full length of the retort by this mechanism.

25 As the coal rises in the retort, it is flooded onto the fire bars 99 which are arranged in pairs alternately moving and fixed, the moving fire bars working transversely to the retort.

30 Movement of the fire bars 99 is obtained through suitable rocking bars 100 and 101 which are rocked to and fro by suitable means located outside of the furnace. The transverse movement of the fire bars 99 in 35 addition to carrying the burning fuel to the inside of the furnace, also conveys the clinker and ash down into the longitudinal pocket 102 and 103 extending parallel to the retort, along the opposite sides thereof. The 40 lower portion of the longitudinal pockets 102 and 103 embrace the grinder cylinders 104 and 105, respectively, these grinder cylinders being rotated in proper direction to crush and discharge the clinkers between 45 the grinder and the skirt portions of the longitudinal pockets 102 and 103, as has been previously described.

Air for supporting combustion enters the 50 stoker through the opening in the bottom of the wind box 106. Upon entering the wind box 106 the air passes upward along each side of the retort and is discharged partly through the openings 107, the remaining air passing through the hollow fire bars 99 and 55 is discharged into the auxiliary air boxes 108. From the air boxes 108 the air enters the fire through narrow openings provided between the fire bars 99.

The furnace shown in Figure 10 is that 60 of the typical rear underfeed stoker type. In this case the clinker and ash are conveyed out into the transverse pocket 110 which extends transversely across the retort adjacent the rear wall 111 thereof. The grinder cylinder 112 is disposed in lower portion of the

transverse pocket 110, this cylinder being rotated in the proper direction to crush and discharge the clinkers between the grinder and the skirt portions of the transverse pocket 110.

In Figure 11 we have shown our improved grinder mechanism in connection with a typical side feed, center cleaned stoker furnace. In this case the coal magazines or 70 hoppers 114 and 115 are located along the sides of the furnace, the coking capacity of the furnace being thereby materially increased. The grate bearers 116 and 117 for supporting the grate 118, being rocked by a suitable rocking bar not shown. The clinkers and other coarse refuse pass into the pocket 119 which extends longitudinally between the grates 118 and are ground out from under the live coals by means of the 75 grinder cylinder 120 which is embraced by the lower skirt portions of the longitudinal 80 pockets 119.

Various modifications will suggest themselves to those skilled in the art, but we intend that these modifications shall come 90 within the scope and spirit of the appended claims.

We claim:

1. In combination, a furnace, a rotatable 95 grinder for removing the refuse of said furnace, said grinder supported in said furnace at an incline to the horizontal plane of said furnace, means for circulating a cooling medium about the interior of said grinder, the upper portion of said grinder adapted 100 to have continuous contact with said cooling medium.

2. In combination, a grinder for cleaning 105 furnaces and the like, a member having fluid inlet and outlet passages extending into said grinder, an inlet pipe communicating with the outer end of said inlet passage for feeding water thereinto, an inlet pipe communicating with the inner end of the 110 said inlet passage for feeding said water into the grinder, a discharge pipe for discharging water from said outlet passage, the inner end of said outlet passage opening into said grinder at a point without said furnace for causing the entire portion of the 115 grinder within said furnace to be subjected to a continuous flow.

3. In combination, a grinder for cleaning 120 furnaces and the like, a member at one end of said grinder having fluid inlet and outlet passages extending into said grinder, said grinder having said end protected from contact with the fire bed of the furnace, said outlet passage opening into said furnace at said end whereby the level of the 125 fluid about said outlet is maintained away from said fire bed.

4. In a grinder for cleaning furnaces and the like, substantially stationary means for feeding cooling water into a rotatable 130

shell, and means adjacent one end of said rotatable shell for discharging the water therefrom whereby said water will contact substantially the entire upper surface of said shell, the hot water being positively forced by thermo-action to a point within the grinder remote from the fire bed.

5. In combination, a grinder for cleaning furnaces and the like, the upper surface of said grinder adapted to be subjected to the heat of the furnace, a member having fluid inlet and outlet passages extending into said grinder, means without said furnace for feeding water into said inlet passage and discharging water from said outlet passage, said inlet passage directing the flow of water to the lower part of the grinder, said outlet passage exhausting water from a level in said grinder where air and steam tends to accumulate, means for maintaining said level remote from the fire bed.

6. In combination, a grinder for cleaning furnaces and the like, the upper surface of said grinder adapted to be subjected to heat of the furnace and lie in a plane inclined to the horizontal, a member having fluid inlet and outlet passages extending into said grinder, means for feeding water into said inlet passage and discharging water from said outlet passage, said inlet passage directing the flow in a downward path to allow the water to rise from the lower part of said cylinder to said upper surface whereby the air and steam formed are forced to move toward said outlet passage.

7. In combination, a grinder for cleaning furnaces, and the like, a member having fluid inlet and outlet passages extending into said cylinder, means for feeding and discharging water from said passages, the upper surface of said grinder adapted to lie at an incline and with a portion thereof in contact with a fire zone of the furnace, said inlet passage feeding water into said grinder so that an upward circulation is created, said circulation terminating at a point immediate said upper surface but remote from the fire zone, said outlet passage opening into said point.

50 8. In combination a furnace, a grinder comprising a hollow cylinder adapted for rotation, said grinder being supported at an incline, closing means at one end of said cylinder forming a bearing closing means at the other end having passages therein for admitting and exhausting a cooling medium from said cylinder and adapted to be stationary relative to said cylinder, said exhaust passage opening into the highest point within said inclined cylinder, said point being remote from the fire bed of said furnace and advancing mechanism for rotating said hollow cylinder.

65 9. The method of cooling a grinder having a cylinder subject to the heat of a

furnace which comprises first inclining the cylinder with respect to the horizontal, next, feeding a stream of cooling fluid in a downward direction to the lower portion so that it tends to flow to the lower end of the 70 inclined cylinder, and finally, removing the heated water which reaches the higher end of the inclined cylinder after it travels along the upper surface by thermo-action.

10. In combination, a rotatable grinder 75 for cleaning furnaces and the like comprising a hollow cylindrical shell, a trunnion member forming a cap at one end of said shell, a stationary member projecting into said shell at the opposite end, said stationary member feeding and withdrawing a cooling fluid, a plate member for closing off this end of said shell, said stationary member and plate having relative rotatable movement, a packing ring within said shell 80 and between said member and said plate, and means adjustably disposed on said member for compressing said packing ring by drawing said stationary member and said plate together.

11. In combination, a grinder comprising, a hollow cylinder adapted for rotation, a cap for closing one end of said cylinder and forming a bearing therefor, a stationary head member for the opposite end of said cylinder, said head member provided with means for feeding water into and discharging water from the interior of said cylinder, a gear on said cylinder, loosely mounted operating arms, a pawl member carried by 100 said arms adapted to engage said gear as the arms are actuated, and means limiting the engagement of said pawl member with said gear.

12. In combination, a grinder comprising, 105 a hollow cylinder adapted for rotation, a cap for closing one end of said cylinder and forming a bearing therefor, a stationary head member for the opposite end of said cylinder, said head member provided with means for feeding and discharging water from the interior of said cylinder, a ratchet gear on said rotatable cylinder, operating arms carrying a pawl member thereon, a loosely mounted member at one end of the 110 cylinder, a detent member carried by said loosely mounted member, a notched plate fixed to said stationary end head adapted for engagement with said detent, means carried by said loosely mounted member for 115 tripping said pawl out of engagement with said ratchet gear for causing a limited predetermined movement to be imparted to said grinder.

13. In a mechanism for periodically advancing a grinder for furnaces and the like, the combination of a grinder comprising, a hollow cylinder, a ratchet gear at one end of said cylinder, loosely mounted operating arms, a pawl carried by said arms, and 120

a tripping member adapted to have predetermined fixed position for tripping said pawl out of engagement with said gear thereby limiting the advancement of said grinder.

14. In a mechanism for periodically advancing a grinder for furnaces and the like, the combination of a grinder comprising, a hollow cylinder, a ratchet gear at one end of said cylinder, loosely mounted operating arms, a pawl carried by said arms, a tripping member adapted to have a predetermined fixed position for tripping said pawl out of engagement with said gear thereby limiting the advancement of said grinder, and means permitting transposition of said tripping member to reverse the advancement of said cylinder.

15. In combination, a grinder for cleaning furnaces and the like, loosely mounted reciprocating arms at one end of said cylinder, engaging means carried by said arms for rotating said cylinder, and means tripping said engaging means at predetermined points thereby permitting said grinder to periodically rotate.

16. In combination, a grinder adapted to be supported for rotation in a furnace, mechanism for rotating said grinder, control means for predetermining the degree of said rotation, said control means permitting the reverse rotation of a predetermined degree.

17. In combination, a grinder adapted to be supported for rotation in a furnace, mechanism for rotating said grinder, a timing plate on said grinder, and a connection between said plate and said mechanism for imparting rotation of predetermined degrees to said grinder.

18. In combination, a rotatable grinder for cleaning furnaces comprising a hollow cylindrical shell, a cap for closing off one end of said shell, a relatively stationary

member passing through said cap, said member feeding a cooling fluid into and discharging it from said feeder, shoulders on said cap and said members, a gasket, and means for drawing said member against said cap for compressing said gasket.

19. In combination, a rotatable grinder for cleaning furnaces comprising a hollow cylindrical shell, a stationary member at one end for feeding a cooling fluid into and withdrawing it from said grinder, a cap rigid with said grinder for closing said end, said stationary member passing through said cap, shoulders on said cap and said stationary member, a gasket, and means for compressing said gasket between said shoulders.

20. The method of cooling with a fluid an inclined grinder subject to the heat of a furnace which comprises, creating two separate streams of cooling fluid in said grinder, one of said streams flowing along the bottom of said grinder, a second stream to flow along the upper surface of said grinder by thermo action, rotating the grinder so that all parts make contact with both streams, discharging said second stream after it reaches the upper end of said grinder.

21. The method of water cooling an inclined grinder subject to the heat of a furnace which comprises, injecting cold water along the lower portion of said grinder and extracting hot water from the upper surface of the interior, the movement of said stream along said upper surface being effected by a rise in temperature and rotating the grinder to bring its surface in contact with both streams.

In witness whereof we hereunto subscribe our names this 10th day of August, 1920.

ALFRED LOTZ.

CHARLES J. DAVIDSON.

WILLIAM J. KENNEY.
